INVENTOR

Alfred C. Schmohl,

BY

W. H. Maubel

ATTORNEY

UNITED STATES PATENT OFFICE

ALFRED C. SCHMOHL, OF BEAVER FALLS, PENNSYLVANIA, ASSIGNOR TO PRESSED STEEL CAR COMPANY, OF PITTSBURGH, PENNSYLVANIA, A CORPORATION OF NEW JERSEY

CAR CONSTRUCTION

Application filed August 14, 1929. Serial No. 385,872.

My invention relates to cars, and particularly to the type known as cane cars, in which it is desired to obtain the maximum capacity for a given over-all length of underframe.

An object of my invention is to provide an end construction for a car combining maximum strength with maximum capacity for a given length of underframe.

10 Another object of my invention is to provide a method of securing the corner post to a car in which the corner post is placed at the end of the car.

Referring now to the drawings, Fig. 1 is a portion of the end of the car showing the method of securing the corner post to the end sill; Fig. 2 is a portion of the side of the car showing the method of attaching the corner post to the side sill; Fig. 3 is a section 20 taken along the lines 3—3 of Fig. 1; Fig. 4 is a modification of the intermediate post shown in Fig. 3.

Referring now to the drawings where like characters refer to like parts, reference 25 character 1 indicates the end of a car having end sills 2, side sills 3 and corner posts 4. As shown in Fig. 1, the side sills are framed into the end sills, but it is to be understood that the end sills and side sills can be 30 formed with a butt joint and a connecting member placed between them. The corner post 4 is placed flush with the end sill and is secured to the outside face of the side sill and extends substantially the full depth of 35 the member. Extending transversely of the car and connected to the top of the corner post 4 is a tie bar 5. Spaced transversely of the car and secured to the tie bar 5 and end sill 2 are intermediate posts 7. The 40 posts 7 are riveted directly to tie bar 5 and have a gusset member 8 securing them to the end sills. The inner edge 9 of the corner post 4 slopes upwardly and towards the end 45 of the car and has secured thereto a member 10 forming the end wall of the car which member is also tied to the side sills 3.

By moving the end post out flush with the end sill the maximum capacity for a given length of underframe is obtained and by extending the corner post substantially the

full depth of the side sill member a sufficient number of rivets can be placed through the post and side sill to obtain an equal or greater shearing stress in the connection than bending strength in the corner post. The gusset member 6 attached to the end of the corner post and to the end sill also extends substantially the full depth of the end sill and strengthens the connection against racking stresses which it will be subjected to in service.

The plate 10 forming the end wall being attached to both corner posts and to the side sills greatly strengthens the end wall construction and by being sloped outwardly towards the end of the car provides a greater capacity than could be obtained were the end wall made vertical.

Although the car has been described as having a solid end wall construction it is to be understood that the plate 10 may be dispensed with under some conditions and the method shown of attaching the post to the side sill and end sill will develop sufficient strength to meet all service conditions.

A modification of the intermediate post 7 is shown in Fig. 4 in which the pressed member 12 may be substituted for the structural member 7. The member 12 is supported on the end sill member 2 and secured thereto by the members 13. When an end wall 10 is used the wall 10 is secured to the sloping side 14 of the member 12.

Having thus described my invention, what I claim as new and desire to secure by Letters Patent is:

1. In a car construction an end sill, a side sill, and a corner post, said corner post being flush with said end sill and attached to said side sill, a gusset member secured to said end sill and corner post, said corner post sloping upwardly and outwardly towards the end of the car from the side sill.

2. In a car end construction combining maximum strength with maximum capacity, an end sill, side sills and corner posts, said corner posts being secured to the outer face of said side sill and flush with said end sill, the inner edge of said post sloping upwardly and towards the end of the car and a mem-

ber secured to the sloping edges of said posts and to the side sills.

3. In a car construction in combination, a side sill and a corner post, said corner post being secured to said side sill and extending substantially throughout the depth thereof, one of the side edges of said post sloping upwardly from the side sill towards the end of the car and a member connecting said sloping edge and side sill.

4. In a car construction an end sill, side sill and corner post connected together, said corner post being secured to the side sill, a gusset plate connecting said corner post and end sill, said corner post and gusset plate being trapezoidal in form.

5. In a car construction comprising an end sill, side sills and corner posts connected together, intermediate posts secured to said end sill and spaced transversely thereof between the corner posts, said corner posts extending substantially the full depth of said sills to which they are secured, said corner posts and intermediate posts sloping upwardly from the sill outwardly towards the end of the car.

ALFRED C. SCHMOHL.
